UNITED STATES PATENT OFFICE

FRANK M. CREIGHTON, OF AMERICUS, GEORGIA, AND WILLIAM E. GRAY, OF MEMPHIS, TENNESSEE, ASSIGNORS TO MOORE DRY KILN COMPANY, OF JACKSONVILLE, FLORIDA, A CORPORATION OF FLORIDA

DRY KILN

Application filed April 13, 1926. Serial No. 101,762.

Our invention relates to an improvement in dry kilns, and more particularly of the so-called charge kiln type.

The fundamental feature of this invention is the attainment of the uniformity of heat and humidity throughout the entire kiln. This is attained by the perfect control of the elements or factors, such as heat, humidity, and circulatory movement of the air of the kiln, that contribute to bring about this uniformity.

Our results are obtained by conditioning the air in the kiln by properly heating, humidifying and circulating and recirculating the air in the kiln uniformly throughout the entire interior of the kiln without admitting fresh air from the outside. As a result, the air in the kiln is brought to the required condition for the attainment of these results in a relatively short space of time after the operation of the kiln is started, thus appreciably reducing the time required for the curing of the contents of the kiln. All of this is accomplished by the use of comparatively simple mechanism.

The means for accomplishing our objects include a closed kiln in which the material under treatment is placed, means for heating and means for humidifying the air confined within the kiln, and means for circulating and re-circulating the conditioned air by simultaneously withdrawing it from the ends of the kiln, and re-heating it, and returning it back into the lower portion of the kiln in the region of the center, whence it rises and re-circulates in countercurrents at the top, being again withdrawn at the opposite ends and re-circulated as before in continuous cycles, with the attendant result that an approximately uniform temperature and uniform humidity is maintained throughout the entire interior of the kiln, and until the contents shall have been cured and is ready to be removed from the kiln.

In the accompanying drawings:

Fig. 1 is a vertical longitudinal section;

Fig. 2 is a horizontal section;

Fig. 3 is an enlarged transverse section on the line 3—3 of Fig. 1, looking in the direction of the arrow.

The kiln illustrated is a charge kiln. By charge kiln is meant one in which the material is placed in the kiln and subjected to the curing process for the required length of time, and then is bodily removed.

The number 1 represents the kiln. This may have doors 2, at one or both ends, and it has ventilators 3 of any approved type in the roof.

The numeral 4 represents heating-coils. These may be arranged in any approved manner, and are located at the bottom of the kiln usually beneath the rails 5. Spray pipes 6 may be arranged wherever desired to meet the requirements. In the illustrated form of the kiln there are shown four such pipes extending longitudinally of the kiln, two at the top spraying downwardly, and two at some point near the bottom spraying upwardly. These sprays are regulated by hand or control regulators (not shown). These pipes are at opposite sides of the kiln.

At opposite ends of the kiln are intake hoppers 7. These are preferably covered over by screens 8, and the conditioned air of the kiln is drawn in opposite directions downwardly into these air inlets or hoppers as indicated by the arrows. From these air intakes or hoppers, an air conduit or conduits 9 extend inwardly in opposite directions, or toward the center preferably so that their discharge ends 10 extend far enough beyond each other to insure a discharge of their contents in opposite directions into the kiln, and sufficiently separated to prevent the two discharges from materially influencing each other. The air in these conduits is moved forward toward the center and accelerated by any suitable mechanism, as for instance jets 11 of steam or compressed air, or fans if desired, two of these being shown in each of the two conduits illustrated. These jets are supplied by a pipe 12 controlled by some form of simultaneous control which may be in the form of a hand-valve or regulator control 13.

By this arrangement of mechanical means, such as air conduit or conduits 9, which withdraw the air of the kiln simultaneously from opposite points and return it to and dis-

charge it at a point in the region of the center of the kiln, with means for accelerating its flow through these conduits, and means for properly heating and humidifying the air, we are enabled to provide a perfect circulatory movement thereof within the kiln in the direction of its natural movement, and without adding any fresh air from the outside, and while this circulatory movement of the air is in progress and under constant and substantial uniform agitation, the temperature and humidity are kept uniform and also under control. Thus here in this or these conduits 9, the returning air is re-heated and re-conditioned in preparation for re-circulation through the kiln.

From the foregoing, it will be seen that we have means for cooling and conditioning the air in filtration and propelling the same in the direction of the natural movement, also means for increasing or decreasing the volume of conditioned air which is circulated and re-circulated longitudinally of the kiln, and means for controlling the relative humidity of the air at the center of wet end of the kiln by moving a greater or less amount of air from the hotter and drier part of the kiln, and finally means for obtaining an approximately constant relative humidity of the air in all parts of the drier without lowering the gradient of temperature or relative humidity.

In this connection, attention is called to the scale of figures indicated in Fig. 1, which are taken from the readings of temperature and humidity at the various points indicated, thus showing substantial uniformity maintained by our improved circulatory system at all points throughout the kiln. The spray pipes are arranged to assist in giving this universal humidity condition, they being regulated by hand or control regulators.

In addition to the humidity spray pipes 6, located at the sides of the kiln and running throughout its length, we have provided a system of sprays in the lower portion of the kiln, extending approximately through the longitudinal center. These are indicated by the spray pipes 15. These are connected by a pipe 16 and supplied by the main pipe 17, and a hand or automatic valve 18 is arranged to control these sprays. Thus, the heating, ventilating, and humidifying, all cooperate and unitedly enter into the general scheme of maintaining uniformity of temperature and humidity throughout the entire interior of the drying chamber.

In conclusion, it may be stated that while the present invention has been referred to as a charge kiln, it is perfectly possible to use it as a progressive kiln, this being done by the proper use of the valves.

We claim:

1. A kiln of the character described, including a chamber, ventilators at the top, a

heat supply at the bottom, sprays for supplying humidity, air intakes at opposite ends, conduits leading from the intakes in opposite directions beyond the center, and discharging in opposite directions away from each other, and jets located in the conduits.

2. A kiln of the character described including a chamber, ventilators at the top, a heat supply at the bottom, sprays for supplying humidity, air intakes at opposite ends, conduits leading from the intakes in opposite directions beyond the center, and discharging in opposite directions away from each other, jets located in the conduits, and means for the simultaneous control of the jets.

3. A charge kiln including a longitudinal drying chamber having air inlets arranged across said chamber approximately at the opposite ends thereof for withdrawing air from the chamber, the conduits communicating with the air inlets for directing the air therefrom toward an intermediate portion of the chamber.

4. A charge kiln including a longitudinal drying chamber having an opening at an end thereof for the intake or discharge of material, and conduits communicating with the chamber approximately at the opposite ends thereof for withdrawing air from said chamber, said conduits extending in opposite directions at an intermediate portion of the chamber and discharging in approximately opposite directions.

5. A drying kiln including a longitudinal drying chamber, and conduits communicating with the chamber approximately at the opposite ends thereof for withdrawing air from said chamber, said conduits extending in opposite directions to points beyond the ends of each other, and discharging in approximately opposite directions.

6. A drying kiln including a longitudinal drying chamber, conduits communicating with the chamber approximately at the opposite ends thereof for withdrawing air from said chamber, said conduits extending in opposite directions from said opposite ends to points beyond the ends of each other, each of said conduits discharging in a direction opposite from the end of the chamber from which said conduit extends.

7. A drying kiln including a longitudinal drying chamber, conduits communicating with the chamber approximately at the opposite ends thereof for withdrawing air from said chamber, said conduits extending in opposite directions from said opposite ends to points beyond the ends of each other, each of said conduits discharging in a direction opposite from the end of the chamber from which said conduit extends, and means for forcing the circulation through said conduits.

ly opposite directions to points beyond the ends of each other, and discharging a drying medium in approximately opposite directions.

5 9. A charge kiln having a longitudinal drying chamber, and conduits communicating with said chamber and withdrawing the drying media from the region of the opposite ends, each of said conduits extending beyond the center and discharging said drying media.

10 10. A charge kiln having a longitudinal drying chamber, and conduits communicating with said chamber and withdrawing the drying media from the region of the opposite ends, each of said conduits conveying said drying media beyond the center and discharging in the direction of the opposite end from which said conduit extended.

15 11. A charge kiln comprising an elongated drying chamber having doors at the opposite ends thereof, hoppers extending transversely of the drying chamber in the regions of the doors, and conduits communicating with said hoppers and extending to and discharging in intermediate portions of the chamber.

20 In testimony whereof we affix our signatures.
